[57] CLAIM

The ornamental design for a combined induction and exhaust manifold for an internal combustion engine, substantially as shown.

DESCRIPTION

FIG. 1 is an elevational view of the combined induction and exhaust manifold for an internal combustion engine embodying my new design and taken from the front side thereof.

FIG. 2 is an elevational view taken from the rear side thereof.

FIG. 3 is an elevational view taken from the left side thereof.

FIG. 4 is an elevational view taken from the right side thereof.

FIG. 5 is a plan view taken from the top thereof.

FIG. 6 is a plan view taken from the bottom thereof.
